CONTROLLER

Hoel L. Bowditch, Sharon, Mass., assignor to The
Foxboro Company, Foxboro, Mass., a corpora-
tion of Massachusetts

Application August 21, 1946, Serial No. 692,102

28 Claims. (Cl. 121—41)

1

This invention relates to pneumatically op-
erated instruments used in connection with meas-
uring and/or controlling variable conditions of
industrial processes.

Industrial processes utilize devices to measure
variable conditions such as temperature, pres-
sure, flow, chemical concentration, etc., and gen-
erally utilize control apparatus to maintain such
variable conditions at a desired value by ma-
nipulating some variable such as flow of liquid,
heat, cold, etc. which affects the controlled vari-
able.

It is an object of the present invention to pro-
vide improved apparatus for measuring and/or
controlling such variable conditions.

A further object is to provide improved ap-
paratus capable of measuring and controlling in-
dustrial processes requiring a high degree of ac-
curacy of measurement and control, and which
apparatus is readily and simply applied to various
processes.

A further object is to provide such apparatus
which requires a minimum of factory adjust-
ments and which may be serviced in the field with
a minimum requirement of skilled labor.

A further object is to provide control apparatus
which, while connected to the process, may be
readily shifted from automatic to manual con-
trol and vice versa.

These and other apparent objects and advan-
tages of this invention are obtained by the means
described in the following specification and may
be more readily understood by reference to the
accompanying drawings wherein:

Figure 1 is a front elevation of measuring and
control apparatus embodying the present inven-
tion and shows a so-called direct action adjust-
ment of the controller;

Figure 2 shows diagrammatically certain parts
of the control apparatus of Figure 1, the parts
being separated one from another in the draw-
ing for purposes of explanation, but being pneu-
matically and mechanically connected together
to operate in the same manner as is the control
apparatus of Figure 1;

Figure 3 is a perspective view of movement and
follow-up assemblies of the control apparatus
shown in Figure 1, and shows a so-called reverse
action adjustment of the controller;

Figure 4 is a detail horizontal section taken
on line 4—4 of Figure 1, but with the reverse ac-
tion adjustment of Figure 3, and shows details of
the movement assembly and of the bearings sup-
porting a floating lever;

Figure 5 is a detail vertical section taken on

line 5—5 of Figure 1 but with the reverse action
adjustment of Figure 3, and shows mechanism for
adjusting the proportioning band of the control
apparatus of Figure 1, the bellows assembly, and
further details of the floating lever of Figure 4;

Figure 6 is a detail section taken on line 6—6
of Figure 4, and shows details of a flapper-nozzle
mechanism;

Figure 6B (Sheet 9) shows in three views three
extreme adjustments of the nozzle-flapper
mechanism;

Figure 7 is a detail vertical section taken on
line 7—7 of Figure 4, and shows the movement
assembly, floating lever, and bellows construction
in greater detail;

Figure 8 shows diagrammatically how the con-
trol apparatus of Figure 1 may be connected up
to control the liquid level of a process;

Figure 9 is a detail side view of a pen-arm sup-
porting shaft;

Figure 10 is a detail front view of the pen-arm
supporting shaft of Figure 9;

Figure 11 is a detail vertical section taken on
line 11—11 of Figure 9;

Figure 12 is a section taken on line 12—12 of
Figure 5, and shows a relay valve with an outer
cover plate removed;

Figure 13 is a section taken on line 13—13 of
Figure 5, and also showing the relay valve;

Figure 14 is a horizontal section taken on line
14—14 of Figure 1, and shows further details of
the relay valve;

Figure 15 is a section taken on line 15—15 of
Figure 14, and shows details of a restriction sup-
plying the nozzle of the control apparatus of
Figure 1 with a restricted flow of air;

Figure 16 is an exploded view of the relay valve
and its support, and shows the passage in the
support;

Figure 17 is a detail section taken on line
17—17 of Figure 1, and shows the nozzle con-
struction and mounting;

Figure 18 is a diagrammatic view showing three
positions of a transfer switch used in the appa-
ratus of Figure 1 to pneumatically connect parts
of the apparatus in different ways (a fourth posi-
tion being shown in Figure 2); and

Figure 19 is a detail vertical view of the dia-
phragm of the relay valve.

Before describing the controller of Figure 1,
reference will be made to Figure 8, and to a brief
description of problems involved in controlling an
industrial process.

In Figure 8, a liquid level process is diagram-
matically shown comprising a tank *a*, having two

inlet pipes *b* and *c*, and an outlet pipe *d* provided with a restriction *e*. Liquid flows into tank *a* through both pipes *b* and *c*. The flow through the pipe *b* may be varied by means of a hand valve *f*, and represents a variable load that may be placed on the process. The liquid flow into the tank through pipe *c* may be regulated by a conventional pneumatically-operated diaphragm motor valve *g*. The diaphragm motor valve *g* is operated by a pneumatic output control pressure from a control instrument *h* which, in response to the hydrostatic head in the tank *a*, converts an air supply to the controller into a pneumatic output control pressure.

In this process the flow of liquid out of the tank through the outlet pipe *d* at any moment depends upon two factors: (1) the liquid level (hydrostatic head) in the tank *a* which is the controlled variable, and (2) the amount of fixed restriction *e* in the outlet pipe *d*. The greater the hydrostatic head in the tank *a*, the greater will be the outflow through the pipe *d*.

Under equilibrium conditions, the flow out through the pipe *d* will equal the inflows through the pipes *b* and *c*. In other words, a hydrostatic head is established in the tank *a* sufficient to make the outlet flow *d* equal the sum of the inflows *b* and *c*. In this process it is desired to control the level in the tank *a* at a level designated by the arrow *k*, and at this level the flow out through the pipe *d* is always the same.

The flow into the tank *a* through the pipe *b* is normally an uncontrolled flow, i. e., one that arbitrarily changes and so represents the change of load or demand placed on the process, and over which the controller *h* has no control. The flow through the pipe *c* is the flow regulated by the controller, and so is the manipulated variable i. e., the variable that is changed in order to make the total flow into the tank *a* that which is required to hold the level at the value *k*, regardless of the load placed on the process. Thus, variation in the flow into the tank through the pipe *b* varies the demand on the process, and varies the value which the controller will have to maintain the manipulated flow through pipe *c* to hold the level at the desired value.

The varying degrees of difficulty of controlling processes such as is diagrammatically shown in Figure 8, and of controlling related processes containing more tanks and connecting resistances, is discussed in the Philbrick Patent 2,360,889, issued October 24, 1944. It is sufficient to point out in this specification that the problem of controlling with the desired accuracy difficultly controlled processes has to some extent been solved by controllers such as disclosed in the Mason Reissue Patent 20,092, in the above-mentioned Philbrick patent, and in the Mason application Serial No. 385,493, filed March 27, 1941, now Patent No. 2,476,104, issued July 12, 1949.

One of the ever present problems, however, in the manufacture of such controllers is that of eliminating friction and dead space which seriously adversely affect the overall performance of control instruments. It is another object of the present invention to provide improved mechanism in which manufacturing costs are reduced without introducing into control mechanism objectionable friction or dead space.

Referring now to Figure 1, the controller there shown may be readily adapted to control many different types of industrial processes, and in the present description will be described as controlling the liquid level of the process shown in Fig-

ure 8. In Figure 1, a measuring element *10* is made responsive to the liquid level in the tank *a* of Figure 8. Through linkage mechanism of a movement assembly generally indicated by *11*, the element operates a pen arm *12* which moves over a circular chart *9*, of which only a fragment is shown, and indicates the value of the liquid level at all times.

The movement assembly *11* is connected by a link *13* to a floating lever generally indicated at *14* of a control assembly generally indicated by *15*. The control assembly *15* is pneumatically operated, and the output of its operation is pneumatic output pressure which goes to the diaphragm motor *g* of Figure 8.

Because so many of the operating parts in Figure 1 are hidden one behind the other, reference will now be made to Figure 2 for a general discussion of and the operation of the parts of the instrument of Figure 1. The measuring element *10* is conventional and comprises a spiral hollow tubing. It has one end *10a* fixed with respect to a back plate *53* supporting the instrument, and a movable end *10b*. Variation of fluid pressure inside the hollow element *10* causes the movable end *10b* to move; i. e., with increase of pressure it moves clockwise, and with decrease of pressure it moves counterclockwise.

The interior of element *10* is connected by tubing *10c* to a conventional pressure transmitting device *10d* which may be placed in the bottom of the tank *a* of Figure 8. Variation of the hydrostatic pressure at the bottom of the tank *a* flexes a diaphragm *10e* covering the device *10d*, and varies the pressure of the fluid in tubing *10c*. The free end *10b* thereby assumes positions proportional to the level of the liquid in tank *a*.

The measuring element *10* has conveniently secured with respect to its free end *10b* a lever *10f* which is part of a bell crank and which moves with the free end *10b* as shown in U. S. Patent 2,209,910 issued to C. D. Young. The lever *10f* is connected by a link *16* to arm *17f* of a lever assembly generally indicated at *17*, and pivoted about a fixed axis *A—A*. The lever *17* has a forwardly extending L-shaped arm *18* which carries pen arm *12*, Figure 1.

Lever *17* is connected by a link *19* to differential bell crank *20*, pivoted about a floating axis *B—B* and supported by a supporting frame *21* also pivoted about the axis *A—A*. The details of the lever *17* and crank *20* and the supporting frame *21* are shown in Figures 3, 4, 7, and 9-11, and will be described in detail following the present thumbnail sketch of the instrument.

The bell crank *20* is so connected by the link *13* to a floating lever generally indicated at *14* of the control assembly *15*, that the horizontal position of the upper end *14a* of the floating lever *14* is at all times caused to assume a position corresponding to the deviation of the level of the liquid in the tank *a* from the set point of the controller as determined by the location of the axis of the crank *20* as will be described (Figure 8). The floating lever *14* carries a pin *22* which operates a valve-operating lever *23*, fixed to and supported by a shaft *24* and urged against the pin *22* by a hair spring *25*.

The shaft *24* has fixed to it and supports a flapper valve *26*, which cooperates with a nozzle *27* of a conventional nozzle-flapper valve assembly such as described in the Philbrick Patent 2,360,889. The nozzle *27* is supplied with a restricted flow of air through a passage *28*, a nozzle volume *28a*, a passage *28b*, a restriction generally

indicated at 29, and a supply chamber 30 forming part of a relay valve generally indicated at 31. Air is conducted to chamber 30 by a pipe 32 which connects with a transfer switch generally indicated at 33, and the transfer switch 33 is connected with the main air supply pipe 35 by a pipe 34.

As will be described in greater detail, the flap-
per-nozzle 26-27 varies the air pressure in a
chamber 36 of the relay valve 31, and in so
doing varies the pressure on a diaphragm 37
thereof with the result that the output pressure
of the relay valve varies with the operation of
the flapper-nozzle valve 26-27. The output pres-
sure of the relay valve goes through a passage
38, a pipe 39, to the transfer switch 33, and is
conducted from the transfer switch through a
pipe 40 and a passage 41 to a proportioning or
follow-up bellows 42 of a bellows assembly gen-
erally indicated at 43. The output pressure from
the relay valve is conducted also to the diaphragm
motor valve 9 through a pipe 48, and the output
of the relay valve is the output pressure of the
controller.

As will be described in greater detail, when the
flapper valve 26 moves further to cover the nozzle
27, thereby further restricting the flow of
air from the nozzle 27, pressure builds up back
of the nozzle 27 and in the chamber 36 of the relay
valve 31, whereupon the relay valve operates to
increase the pressure in the passage 38, the pipe
39, the pipe 40, and in the proportioning bellows
42. Movement of the flapper valve 26 away from
the nozzle 27 causes a reduction of the pressure
back of the nozzle, and causes the relay valve
to reduce its output pressure by exhausting more
air to atmosphere through an exhaust port 44,
and reducing the air flow to passage 38 from the
air supply chamber 30. This action serves to
reduce the pressure in the proportioning bellows 42.

As described in the Philbrick patent, the nozzle
27 emits only a small jet of air, and the move-
ment of the baffle 26 with respect to the nozzle
required to produce change of pressure back of the
nozzle to operate the relay valve to produce
a maximum change of output pressure is prefer-
ably less than .001 of an inch. So long as the
flapper is within this .001 of an inch of its travel
from the nozzle, it is considered to be within
its operating range, and to be "tangent" to the
nozzle.

The proportioning bellows 42 is opposed by
a reset bellows 45. The outer ends of the bel-
lows 42 and 45 are fixed, but their inner oppo-
sing ends are free and operate against a flexure
spring 46, rigidly secured at its end 46a. The
flexure spring 46 is so arranged that its free end
46b moves under the differential force exerted
by the pressure in the proportioning bellows 42
and the pressure in the reset bellows 45. The
flexure spring provides a spring characteristic
in addition to the inherent spring characteristic
of bellows 42 and 45; and for every pressure dif-
ference existing in the bellows, the free end of
the flexure spring assumes a position correspond-
ing to the pressure difference. The effective op-
erating areas of the bellows 42 and 45 are equal so
that when equal pressures exist in the bellows,
the free end 46b is always positioned at the neu-
tral (norm) position, axis D—D.

The free end 46b supports a shaft 47 to which
is secured the lower end 14b of the floating lever
14. This arrangement provides for operating the
lever 14 about its end 14b, so that the upper end

14a may be moved horizontally by the measuring
element 10; and the lower end 14b is movable
vertically by the bellows assembly. Thus the
motion of pin 22 carried by the floating lever 14
may be considered as the resultant of two com-
ponents of motion substantially perpendicular to
each other, one from the measuring element 10,
and the other from the proportioning bellows.

Vertical movement of the floating lever by the
proportioning bellows 42 causes the pin 22 car-
ried by the floating lever to operate the flap-
per-operating arm 23, and so to operate flapper valve
26. The reactions of the flapper-nozzle 27-26,
relay valve 31, and the proportioning bellows 42,
are such as to maintain the flapper 26 tangent
to the nozzle 27 in the same manner as described
in the Philbrick patent. If the pin 22 is holding
the flapper 26 too far from the nozzle 27 within
the .001 inch range of operation, the reaction
of the relay valve 31 and proportioning bellows
42 is to lower the floating lever 14, and the pin
22 to establish the correct nozzle-flapper rela-
tionship. If the pin 22 is holding the flapper too
close to the nozzle within the operating range,
then the reactions are such as to raise the pin
to establish the correct nozzle-flapper rela-
tionship.

Since the pin 22 is also moved by the measur-
ing element 10, the result of the interaction of
the parts is to cause pressure in the bellows 42
to change in accordance with changes in the po-
sition of the measuring element 10, i. e., as moves
the measuring element, so move the bellows 42
and the flexure spring 46.

With the adjustment of the parts as shown in
Figure 2, a direct action type of operation is ob-
tained in which increasing pressure in the measur-
ing element produces increasing output pres-
sure of the controller. Now, as the pressure in
the measuring element 10 increases, thereby mov-
ing the end 14a of the floating lever 14 to the right
and so moving the pin 22 to the right, the flap-
per-operating arm 23 is turned clockwise by the pin
22, thereby tending to cause the flapper 26 to
cover the nozzle 27. But as this action takes
place, the relay valve 31 increases its output
pressure, and the pressure in the bellows 42,
thereby causing the floating lever 14 to rise and
the pin 22 to rise to counteract the clockwise ac-
tion of the flapper-operating arm 23, whereby
the tangency between the nozzle and the flapper
is maintained at all times. This action causes
the pressure in the bellows 42 to increase in cor-
respondence with movement of the measuring
element.

The actions and reactions of the nozzle-flap-
per, the relay valve 31, and the proportioning
bellows 42 are made so fast that for all practical
purposes any changes in position of the measur-
ing element 10 are immediately and completely
reflected accurately and correspondingly in
change of pressure in the bellows 42; and any
rate of change of position of the measuring ele-
ment 10 is reflected in a corresponding rate of
change of pressure in bellows 42.

This description of the operation omits from
consideration the effect of bellows 45, and in fact
the bellows 45 may be omitted, in which event
the controller operates as a proportional con-
troller as just described. The operation of a
proportional controller, as more fully described
in the above-mentioned Mason Patent 2,476,104,
serves to make changes in the output pressure
of the controller proportional to change of the
condition being controlled.

The instruments of Figures 1 and 2, with the reset bellows in operation, is a proportioning-plus-floating controller, and as described in the above-mentioned Mason patent, this controller has the added feature over and above that of the proportioning controller of causing the process to balance out at a so-called "set point" value, regardless of the demand placed on the process. The set point is that particular value of temperature, pressure, flow, etc. that the proportioning-plus-floating controller will maintain regardless of the demand on the process.

Still referring to Figure 2, the interior of bellows 42 is connected with the interior of the bellows 45 through a passage 49, a restriction generally indicated at 50, and a passage 51. The restriction illustrated is a variable restrictor of a construction described and claimed in the Bilyeu patent application, Serial No. 559,640, filed October 20, 1944, now Patent No. 2,432,082. The variable restriction comprises a bent tube 50a having a flattened or oval cross-section and having one end mounted in a fixed base 50b. The tube 50a may be bent to different curvatures by a movable base 50c and a manually operable lever 50d. A freely flexible return tube 50e connects the movable block 50c with base 50b, and with the passage 51. By changing the curvature of the tube 50a, the restriction that it offers to the flow of air through it changes. The tighter its curvature, the more restriction it offers, and vice versa.

When equal pressures exist in the bellows 42 and 45, the free end 46b of the flexure spring always assumes its neutral position at the axis D—D. In order to have the nozzle and flapper in their tangent relationship when the free end 46b is in its neutral position, the measuring element 10 must have the upper end 14a of the floating lever in a corresponding neutral position at the axis E—E. When the floating lever 14 is positioned such that its ends 14a and 14b are at their neutral positions, then the pin 22 is in a neutral position at the axis F—F, and the controller mechanism is at its control point setting position.

The position of the end 14a is determined by the setting of the axis B—B of the frame 21, as will be described, and by the position of the measuring element 10. For any given setting of the axis B—B, when the measuring element 10 holds the end 14a at the neutral position, the value of the condition that holds the measuring element in this position corresponds with the control point setting or the set point of the instrument. The mechanism by which the axis B—B is adjusted, is referred to as the control point setting mechanism, and this mechanism will be described later.

Reference will now be made to Figure 3 and to Figure 2 for a brief discussion of the operation of the controller as a proportioning-plus-reset controller. Assuming the "direct action" adjustment of the controller as shown in Figure 2, and a control point setting adjustment to make the height k the value of the control point setting, and assuming an equilibrium condition in which the level is balanced at k , if under these conditions the demand on the process is changed by increasing the flow into the tank through the pipe b, then the liquid level will start rising. As the level rises, the controller acts to increase the pressure on the diaphragm valve g thereby further closing the valve in the pipe c so that as the level rises less and less water flows through

the pipe c. This action will not only prevent the level from rising as far as it would had no control action been made, but will tend to return the level toward its control point value. And eventually the controller will establish a pressure on the diaphragm g such as to balance out the process with the level at the original value of k .

The reason that the controller operates to bring the level back to the control point and does not permit it to balance out above or below the control point is fully described in the above-mentioned Mason application, and so will only be briefly traced in the present specification.

When the measuring element 10 is at its control point position, it holds the end 14a of the floating lever 14 at its neutral position on the axis E—E, and the pressures in the two bellows 42 and 45 are equal and must be so in order properly to position the pin 22 on its axis F—F, which position of the pin holds the flapper in its tangent position.

Assuming again the upset caused by increasing the flow through the pipe b, following the equilibrium condition; this results in the level in the tank a starting to rise because more liquid is flowing into the tank than out of it. The rising level causes the measuring element 10 to assume a rate of change in a clockwise direction, and the end 14a of the floating lever 14 and pin 22 to assume a corresponding movement to the right. The resulting clockwise movement of the flapper-operating arm 23 is offset by the reaction of the nozzle-flapper, the relay valve 31, and the proportioning bellows 42 which served to move the pin 22 upwardly to counteract the rightward movement of the pin 22 and to keep the nozzle and flapper in their tangent relationship. The overall result is that the pressure in the bellows 42 assumes a rate of change corresponding with the rate of increase of the level in the tank a. This increasing pressure change which is transmitted to the diaphragm motor g serves to give the valve in the pipe c a rate of closing. We can assume that the closing action of the valve eventually stops the level in tank a from rising, but unless some additional action is performed the level would not return to its original value because, as the level returned the controller would give the valve in pipe c an opening action. It is the reset action that permits and causes the controller to reestablish the set point value of the level.

If we assume that the pressures in the bellows 42 and 45 were equal and at a value of 8 lbs. before the upset of the process occurred, then when the upset occurred the pressure in the bellows 42 immediately started increasing above the 8 lbs. in order to move the floating lever 14 upwardly in order to keep the nozzle and flapper tangent. And at any instant the amount that the pressure in bellows 42 was above that in bellows 45, corresponded with the amount that the measuring element 10 had moved the floating end 14a from its neutral position. But the pressure in the bellows 42 being higher than that in the bellows 45 causes air to flow through the restrictor 50 into the bellows 45, thereby causing pressure in the bellows 45 to assume a rate of increase, which rate of increase is proportional to the pressure difference between bellows 42 and 45. The increasing pressure in the bellows 45 causes a corresponding increase of pressure in the bellows 42, for the reason that in order to hold the nozzle-flapper in a tangent relationship the pressure in the bellows 42 must be above that

in the bellows 45 by an amount corresponding with the amount that the measuring element 10 has moved away from its control point position. The rate at which the pressure in bellows 45 increases is, therefore, related to the deviation of the level *k* from its control point value. Thus, there are two factors now causing an increase of the pressure on the diaphragm motor *g*: (1) the rising liquid level (the proportioning control action); and (2) the increasing pressure in the bellows 45 caused by the deviation of the level from the control point value (the reset control action).

When the level in the tank *a* stops rising as a result of the closing action on the valve *g* and commences to lower, the pressure in bellows 42 responds by tending to decrease in the same way the pressure increased while the level was rising. But so long as the level is above the control point value, end 14a of the floating lever 14 is at the right of its norm position E—E, and the pressure in bellows 42 holds above the pressure in the bellows 45, in order to hold the nozzle and flapper in their tangent relationship. The pressure in bellows 42 being above that in bellows 45 causes the pressure in bellows 45 to continue to increase and, in effect, tends to increase the pressure in bellows 42 at the same rate. So, as the level lowers toward the control point value, the measuring element 10 moves the end 14a of the floating lever toward the neutral axis E—E with the result that, although the increasing pressure in the bellows 45 is tending to increase the pressure in the bellows 42, the movement of the measuring element 10 is tending to decrease the pressure in the bellows 42. But because the pressure in the bellows 45 will continue to change so long as the end 14a of the floating lever 14 is away from the neutral axis E—E, i. e., control point position, the instrument acts to prevent the level in the tank *a* from balancing out at any but the control point value.

Eventually when the control point value is reached under the condition of the assumed increased demand, the pressures in the two bellows 42 and 45 will be equal but will be above the previous value of 8 lbs. The pressure will be above the previous value of 8 lbs. by an amount required to hold the valve *g* in whatever new position is required to meet the change of demand as placed on the process by increasing the flow through the pipe *b*.

The amount of the restriction of the restrictor 50 is adjustable to match the overall slowness of the process as described in the Mason application.

Returning now to the movement assembly, this assembly is provided to facilitate (1) aligning the measuring element and the pen arm so that the pen arm points to the correct index on the chart of the value being measured by the measuring element 10; and (2) to facilitate setting the control point to the desired value.

Referring to Figures 1, 2, 3, 4, and 7, the movement assembly is supported on a base 52 secured to the instrument backing plate 53 (Figure 3). Secured to the base 52 by means of built-up posts 54 are inner and outer bearing supporting plates 55 and 56. These plates are provided with holes aligned on the axis A—A, which holes serve as bearings for supporting the lever 17 and its associated pen arm support 18.

Referring to Figures 9, 10 and 11, the lever 17 comprises an inner cut out arcuate section 17a, having a supporting arm 17b to which is suitably secured the L-shaped pen arm support 18, for

supporting the pen arm 12. A shaft 17c passes through the section 17a, and supports a bearing sleeve 17d suitably fixed to a hook-shaped section 17e, and to the driving arm 17f of the lever 17. 5 As shown in Figure 9, the lever 17 and the pen arm support effectively form a U-shaft. Pins 57 are provided on the U-shaft to enter the holes in the plates 55 and 56, which thereby support the U-shaft.

10 The hook-shaped section 17e has a friction drive surface 17g which by the spring action of section 17e presses against a shaft 17h, and normally holds the two sections 17a and 17e against relative angular motion. The shaft 17h is suitably rotatably mounted in the U-shaft, and is provided with a screw-driver slot. By rotating the shaft 17h the angular relationship between the parts 17a and 17e may be adjusted.

This adjustment serves when necessary to bring 20 the pen arm 12 into correct angular relationship with respect to the measuring element 10, i. e., it serves to bring the pen and the measuring element into alignment at any convenient reference point, so that the pen always points to the correct positions on the chart for the different positions of the measuring element 10. The adjustment is made by applying to the measuring element 10 a known value of the variable which the measuring element 10 measures, and then rotating the shaft 17h until the pen arm 12 points to the reference on the chart corresponding to the value applied to the measuring element 10.

35 Referring to Figure 2 (and to Figures 3, 4 and 7 for the details), the frame 21 supporting the bell crank 20 is pivotally mounted on the axis A—A between inner and outer supporting plates 58 and 59, suitably supported by the posts 54. The frame 21 is made up of a U-shaped piece providing spaced inner and outer parallel arms 21a and 21b, whose free ends are suitably spaced by a spacing column 21c secured to the arms 21a and 21b. The frame 21 is pivotally supported from the plates 58 and 59 by pins 21d (Figure 4), extending outwardly from the arms 21a and 21b and entering suitable bearing holes in the plates 58 and 59.

40 Returning to Figure 2, fixed to and extending forwardly from the frame 21 adjacent the pivoted end is an L-shaped arm 21e which carries a control-point-setting indicating pointer 61. The forward end of the arm 21e turns downwardly and carries a pin which is journaled in a supporting plate 60 (Figure 3) supported by the part 54. The indicating pointer 61, secured to the arm 21e 45 is angularly adjustable with respect thereto by means of a conventional micrometer screw arrangement 62. The mechanism for angularly adjusting the frame 21 about the axis A—A to set the control point is described further on in the specification.

45 The differential bell crank 20 supported by frame 21 is suitably secured to a shaft 20a, pivoted on suitable bearings in the frame arms 21a and 21b. The driving arm 20b is connected to the driven arm 17a of the lever 17 by the link 19, and the link 19 is of approximately the same length as the distance that separates the axes A—A and B—B of the crank 20 and lever 17. The driven arm 20c of bell crank 20 is connected 50 by link 13 to the end 14a of lever 14 as above described. The distance between the axis B—B of the bell crank 20 and the point of connection 20d with the link 13 is the same as the distance that separates the two axes A—A and B—B. Also 55 when the controller is controlling the process at

the control-point setting, the point of connection 21d is at the axis A—A.

Referring to Figures 2 and 3, the frame 21 is adjusted about the axis A—A by a link 63 connected to an arcuate spring lever 64, pivotally supported at 65 on an extension of the supporting plate 58. The lever 64 is frictionally driven by its spring-pressed contact against a groove 66 in a control point setting shaft 67, journaled in inner and outer plates 58 and 60, and manually rotated by a control point setting knob 68. The construction of the control point setting mechanism is described in more detail in the copending patent application, Serial No. 660,644, filed April 9, 1946, now Patent No. 2,455,326.

When the condition being controlled is at the set point, as determined by the position of the frame 21, the arm 20c of the bell crank 20 is parallel with the frame 21, and its connection point 20d with the link 13 is centered with respect to the axis A—A. Thus, the length of the link 13 determines the distance between the center of motion A—A of the movement assembly and the neutral position E—E of the end 14a of the floating lever 14. As will be explained, provision is made to adjust the position of pin 22 with respect to the end 14a to align the operating parts.

The control point setting mechanism functions as follows: For a given setting of the frame 21 there is a corresponding position of the measuring element 10 that will position the differential lever 20 in its norm position with the point of connection 21d aligned with the axis A—A. By rotating the control point setting knob 68, the frame 21 is moved about its pivot A—A, and its various positions require different corresponding positions of the measuring element 10 in order to bring the differential crank 20 and the floating lever 14 into their norm position. Since the various positions that the measuring element assumes are determined by the values of the condition being measured, the adjustment of the frame 21 about its axis A—A determines the set point at which the controller will maintain the process being controlled.

The index pointer 21e attached to the frame 21 indicates the adjustment of the frame 21 with reference to the chart, and is so aligned with respect to the frame 21 that it points to the index on the chart at which the controller will maintain the condition being controlled.

To align the indicating pointer 61 of the control point setting device accurately to indicate the set point with reference to the chart, the control point setting knob 68 is turned to bring the point of connection 20d in line with the axis A—A. The micrometer screw 62 carried by the L-shaped extension 21d is then turned to bring the indicating arm 61 into alignment with the position of the pen arm 12. If desired during the adjustment of the micrometer screw 62, the arm 20c of the crank 20 may be locked with respect to the supporting frame 21 by passing a .040" pin through .040" holes 69 provided in the frame members 21a and 21b and in the arm 20c of the crank 20.

This adjustment once made is not affected by subsequent adjustment of lever 17 with respect to the measuring element by turning the shaft 17a as described, because this adjustment does not change the relationship between the pen arm 12 and the indicating arm 61.

The connections between the links and the bell cranks and the bearings supporting the lever 17 and crank 20 are made as frictionless as pos-

sible, and with a minimum of lost motion, so that slightest movements of the measuring element are accurately imparted to the floating lever 14. The construction of the movement assembly disclosed has several distinct advantages. One of them is that the alignment of the parts is readily accomplished. Another is that only a single link 13 is required between the movement assembly and the control mechanism proper. Another advantage is the concentric relationship between the pen, the index pointer and the connection point 21d of the differential crank 20, and the frame 21, which provides that when the pen arm and indicating pointer 61 are aligned at one point on the chart scale, the alignment relationship holds inherently over the full scale. Further, with this construction the position of the connecting link 13 is a measure of the deviation between the pen arm and the indicating pointer 61, which measure holds reasonably accurately throughout the working range of the instrument.

The nozzle-flapper assembly

The details of the nozzle-flapper assembly are best seen in Figures 3, 4, 5, 6 and 7 and 17. Referring to Figures 3, 4, and 7, the shaft 24, supporting the flapper and the flapper-operating lever 23, is freely pivoted between inner and outer supporting plates 70 and 71, respectively, spaced apart by two spacing posts 72. The inner plate 70 is secured to the posts by peening over the ends of the posts extending through the plate. The outer plate 71 and the posts 72 are secured to the outer edge of a gear wheel 73 by screws passing through the gear wheel and threading into the posts. One of the screws 92 is provided with a long head, which limits the extent of rotation of the gear wheel, as will be described. The plates 70 and 71 are provided with holes which freely receive the reduced ends of the shaft 24.

The flapper-operating lever 23 is secured to a sleeve 23a fixed to the shaft 24. A hair spring as shown in Figures 3 and 6, is fixed at its inner end to the shaft 24, and at its other end to the post 72 adjacent the spring. The flapper 26 comprises a thin phosphorous bronze flat strip bent around the shaft 24 and soldered to it. In addition (Figure 6) the flapper is provided with a portion 26a bent back on itself and threaded to receive a micrometer screw 26b by which the angular relationship between the flapper 26 and the flapper-operating lever 23 may be adjusted. The flapper assembly is constructed and assembled to provide a substantially frictionless bearing support for the shaft 24.

The nozzle 27 is threaded into a hollow stud 74, having a hex-shaped head 75 and mounted on the gear wheel 73. The stud 74 passes through the gear wheel 73 into a passage 77 (Figure 17) in a frame casting 76, which forms a support for the control assembly and which provides various passages for air as will be described. The stud thus serves as the shaft for the wheel 73, and the passage 77 the bearing for the shaft.

Between the gear wheel 73 and the frame 76 is placed a suitable gasket 78, which while permitting rotation of the gear wheel with respect to the frame 76, provides a seal which prevents air from escaping between the gear wheel and the frame 76. Referring to Figures 4 and 5, the gear wheel is held in place against the gasket 78 by means of an angle bracket 79 which presses against the end of the hex head 75. The angle bracket 79 is secured to the frame casting 76 by two screws 80, there being sufficient spring in the

angle bracket 79 to hold the gear wheel 73 and the gasket 78 tightly against one another and against the casting 76.

Referring to Figures 5 and 6, the gear wheel 73 is rotated by a pinion gear 88 which meshes with gear wheel 73. The pinion gear 88 and wheel 73 have a 2:1 reduction and are mounted on a shaft 89 supported in the frame casting 76. To the shaft 89 is secured a dial 90, Figures 1 and 3, and provided with indices which show the position of adjustment of the flapper-nozzle by reference to an index pointer 91. Turning dial 90 through 360° turns the gear wheel through 180°.

The dial 90 is shaded as shown to indicate to the operator whether the instrument is adjusted for direct or reverse action.

To prevent the gear wheel 73 from being turned beyond its extreme positions which are approximately 180° apart, one of the screws 92 securing the flapper-supporting frame 71 to the gear wheel 73 is extended as shown in Figure 3. Adjustable screws 93 are provided to adjust the extreme positions of the gear wheel 73.

By mounting the nozzle and the flapper and flapper-operating lever on the gear wheel 73, the gear wheel 73 may be rotated to change the operative relationship between the operating pin 22 of the floating lever 14 and the flapper-operating lever to change the width of the proportioning band of the controller, and to reverse the action of the controller as will be described. Also by mounting these parts on the gear wheel 73, the above-mentioned operative relationship may be changed without affecting the alignment of the nozzle and flapper and their associated parts.

By utilizing the floating lever construction and the free operating connection between the floating lever and the flapper operating arm, the desired proportionality between the motion of the measuring element and the follow-up motor may be obtained by suitably shaping the cam surface of the flapper operating arm. Also because the construction permits the free connection between the floating lever and the flapper operating arm, the possibility of an inadvertent straining of the parts by the follow-up motor means or by the measuring element is eliminated.

Using the construction of the floating lever with its ends operated generally at 90° directions by the measuring element and the follow-up motor, makes it possible to obtain the desired correspondence between the measuring element motion and the follow-up motor motion by the proper shaping of the cam surface of the flapper operating arm, regardless of whether the follow-up motion imparted to the floating lever produces the Watts straight-line motion or whether it produces some motion appreciably departing from the straight-line characteristic.

However, with the construction disclosed which utilizes the Watts straight-line motion on the follow-up mechanism, certain advantages are obtained. Thus with the construction as disclosed, increasing pressure in bellows 42 always moves pin 22 upwardly and so always tends to lift the flapper from the nozzle, regardless of whether the gear wheel 73 is in its "reverse" or "direct" acting position. Changing the gear wheel and its associated parts from "reverse" to "direct" acting position changes the direction of the action of the measuring element on the operating lever 23 but does not change the direction of the action of the bellows 42 on the operating lever.

Referring to Figure 6B, the three extreme positions of the nozzle-flapper mechanism are

shown. In the extreme position entitled "direct open and shut," the axis C—C of the nozzle-flapper has been rotated to its lowermost position, in which position the flapper-operating lever 23 is substantially vertical. With this adjustment, as the measuring element 10 moves the end 14a of the floating lever 14 to the right of the neutral position E—E, the flapper 26 covers the nozzle 27, but the resulting increasing pressure in the proportioning bellows 42 in moving the floating lever 14 upwardly produces substantially no effect on the flapper-operating lever 23, because the contacting surface of the operating lever 23 is substantially parallel to the line of motion of the operating pin 22. As the gear 73 is rotated clockwise to move the axis C—C of the flapper upwardly, a given movement by the end 14a of the floating lever 14 causes less movement of the operating lever 23, and a given movement of the lever 14 by the proportioning bellows 42 causes more movement of the operating lever 23. Result—for a given motion of the measuring element 10 less change of pressure is required in the proportioning bellows 42 to maintain the nozzle and flapper in their tangent relationship. Thus, movement of the gear wheel 73 in a clockwise direction effectively widens the proportioning band of the controller as defined in the above-mentioned Philbrick patent.

But rotation of the gear wheel 73 to the point where the flapper operating lever 23 is disposed in substantially the same horizontal plane as that of the operating lever pin 22 of the floating lever 14, as shown in the "mid position" view of Figure 6B, so arranges the parts that substantially no motion is imparted to the pin 22 by the measuring element. This position might be characterized as an infinite proportioning band adjustment in which movement of the measuring element produces substantially no change of the output pressure of the controller.

When the gear wheel 73 is rotated to the extreme position marked "reverse open and shut" (Figure 6B) the axis C—C of the flapper is in its uppermost position and movement of the end 14a of the floating lever 14 to the right causes the flapper 26 to uncover the nozzle thereby causing the pressure in the bellows 42 to lower. But because the flapper-operating lever 23 is substantially vertical in this position, movement of the floating lever 14 by the proportioning bellows 42 produces no effect and the instrument in this position of adjustment operates substantially as an open and shut controller. With this adjustment, the same movement of the element which produced an increase of output pressure in the direct open and shut position now produces a decrease in pressure. As the gear wheel 73 is rotated counter-clockwise from its extreme position of reverse open and shut position, the proportioning band width of the controller is increased as previously described.

The desirability of adjusting the width of the proportioning band to match the control instrument to the process being controlled is fully described in the Philbrick patent and the Mason patent. The present construction provides a simple and positive mechanism for accomplishing this adjustment.

The overall mechanism for adjusting the proportioning band width may be described as follows: The adjustment serves to vary the amount of pen travel required to change the output pressure of the controller mechanism between its maximum and minimum values. Because the

movement of the flapper with respect to the nozzle is only a fraction of a thousandth of an inch, the controller mechanism may be described as acting to move the operating pin 22 along a path just touching the flapper operating lever 23. Thus the path of movement of the pin 22 is determined by the slope of the operating (cam) surface of the flapper operating lever 23.

Two components of motion move the pin 22. One is the motion of the measuring element that provides a horizontal component of motion. The other is the motion of bellows 42 that provides a vertical component of motion. The ratio of these two components of motion is determined by the angle that the flapper operating lever 23 makes with the floating lever 14. When the angle is small the component of motion of the operating pin 22 due to motion of the bellows 42 is small, and the component of motion due to movement of the measuring element is large, so that only a small motion of the measuring element is required to cause the output pressure of the controller to change between its maximum and minimum values. But as the angle approaches 90° the component of motion produced by the measuring element is relatively small and the component of motion produced by the bellows 42 is relatively large, and a relatively large motion of the measuring element is required to cause the output pressure of the controller to change between its maximum and minimum values.

It is thus apparent that rotation of gear wheel 13 adjusts the angle that flapper-operating lever 23 makes with respect to floating lever 14 and that this adjustment determines the amount of movement of the end 14a (by the measuring element) required to cause the output pressure of the controller mechanism to change between its minimum and maximum values.

The change from so-called "direct action" to "reverse action" is useful in instances where it is desired to have failure of air pressure either close a valve or completely open a valve. With the instrument capable of being operated either as a direct acting instrument or a reverse acting instrument, it may be applied to a type of valve motor which either opens or closes the valve with failure of air supply whichever action is desired.

The mechanical connection between the measuring element follow-up motor 42 and the flapper is constructed as a Watts straight-line mechanism in which movement of the floating lever 14 by bellows 42 imparts a straight-line motion to the operating pin 22. This straight-line motion of the pin 22 by the bellows 42 makes it possible to use a straight-line surface on the operating face of the lever 23 while retaining the desired proportional motion between movement of the measuring element and the movement of the bellows 42. By making the length of the lever 14 sufficiently long so that the distance of the pin 22 to the axis D—D may be made relatively large, motion of lever 14 by the measuring element introduces no appreciable vertical component of motion to the pin 22 thereby aiding in retaining the above mentioned proportional relationship.

Floating lever

Referring to Figures 2 and 3, to adjust the proportioning band width, the axis C—C of the flapper and flapper-operating lever 23 is adjustable around axis F—F (Figure 3). The axis of round operating pin 22 must coincide with the axis

F—F when the operating pin 22 is in a "neutral position" determined by the neutral vertical and horizontal positions of the floating lever 14. These latter positions are determined by the neutral horizontal position of end 14a, and the neutral vertical position of end 14b. Since neither the neutral position of the end 14a nor of the end 14b is adjustable, provision is made for adjusting the operating pin 22 vertically and horizontally with respect to the floating lever 14, to bring the pin 22 into its neutral position concentric with the axis F—F.

To this end, referring to Figure 7, the lever 14 is made up in three sections. An upper section 14c is pivotally connected at 14d to a lower section 14e. The angular relationship between the upper and lower sections 14c and 14e is adjusted by a conventional micrometer screw arrangement 14f, which connects a depending finger of section 14c with 14e.

A third L-shaped section 14g is pivoted at 14h on an extension of the lower section 14e, and carries the operating pin 22. The angular adjustment between the part 14g and the lower part 14e is determined by a conventional micrometer screw mechanism 14k mechanically connecting part 14g with 14e. By adjusting the micrometer screw 14f, the operating pin 22 is effectively moved horizontally to the right or to the left with respect to the ends of the floating lever 14. By adjusting the micrometer screw 14k, the operating pin 22 may be adjusted vertically with respect to the ends of the floating lever 14.

Alignment of operating pin 22 and flapper-operating lever 23

In order to adjust the operating pin 22 and the flapper-operating lever 23 so that they are properly centered, one with respect to the other, and properly aligned with respect to the flapper and nozzle, the control point setting knob 68 (Figures 2 and 3) is rotated to move the frame 21 to bring the connection point 26d in line with the center of rotation A—A of the movement assembly, and an aligning pin is dropped through the holes 69 in the frame 21, and driven arm 20c of the bell crank 20. The control point index 61 is aligned with the pen arm 12 by moving the micrometer screw 62 on the control point index.

Next, the proportioning band adjusting dial 90 is rotated to place the gear wheel 73 in either of its open and shut positions so that the flapper-operating lever 23 is positioned vertically. Now (assuming a supply pressure of 17 lbs./sq. in.) the micrometer screw 14f is adjusted to move the operating pin 22 horizontally until the operating pin so positions the lever 23 as to produce an output pressure of from 3 to 15 lbs. per sq. in. as indicated by a pressure gauge 93 (Figure 2), connected to the output of the relay valve by a pipe 94. During this operation, the restriction-adjusting arm 50d is moved to provide the least resistance possible between the bellows 42 and 45, so that any pressure difference between them is quickly dissipated.

The proportioning dial 90 (Figure 2) is now reversed to move the gear wheel 73 to its other extreme open and shut position. If this reversal produces a change in the output pressure (taking it outside the 3 to 15 lbs. range) then by using equally the micrometer screw 14f and the micrometer screw 26b, and by going back and forth from the two extreme open and shut adjustments of the gear wheel 73, it is possible to

obtain an adjustment which keeps the pressure within the 3 to 15 lbs. range when the gear wheel 73 is in either of its open and shut positions.

To adjust the vertical position of the operating pin 22, the proportioning dial 90 is moved to place the gear wheel 73 in its mid-position between its two open and closed positions, in which position the operating-lever 23 is horizontally disposed. Now, the micrometer screw 14k (Figure 2) is adjusted to bring the output pressure from the relay valve 31 to within the 3 to 15 lbs. range. The gear wheel 73 is now moved to first one of its open and shut positions and then its other open and shut position for the final adjustments of the three micrometer screws 26b, 14k and 14f to keep the output pressure in the 3 to 15 lbs. range as the gear wheel 73 is shifted to its different positions.

As shown in Figures 3, 4 and 5, the floating lever is suitably braced, and the shaft 47 supporting the floating lever from the flexure spring 46 is mounted freely in suitable bearings. An adjustable stop 47a is provided to prevent axial play of the shaft 47.

Bellows assembly

The flexure spring 46 (Fig. 7) is clamped to a support formed in the frame casting 76. Secured to both sides of the flexure spring 46 are plates 95, provided with recesses 96 to receive aligning studs 97 projecting from plates closing the free ends of the bellows 42 and 45. To the plates 95 also is suitably secured the frame or yoke 46b which supports the shaft 47 of the floating lever 14.

Referring to Figure 7, each of the bellows 42 and 45 is made up of metallic bellows, the free ends of which are closed by plates 142 carrying the studs 96.

Referring to bellows 42, its fixed end is closed by a plate 144. Secured to and passing through the plate 144 is a rod 145, having a shoulder 146 to which the plate 144 is soldered. A larger hex-shaped shoulder 147 extends from the rod, and the plate 144 is also secured to one side of this shoulder. The other side is clamped against the casting 76. The rod 145 extends into the bellows 42 and provides a stop limiting the amount that the bellows can be compressed. The rod 145 extends out through the bellows and is threaded at 149. The threads 149 thread into a hole 150 in the casing which serves to tighten the shoulder against a gasket to provide an airtight mounting on the casting 76. A cover 151 closes the lower end of the hole 150. A passage 152 is provided through the shoulder portions of the rod 145, and connects the interior of the proportioning bellows with the hole 150 in the casting. A passageway 41 in the casting 76 serves to connect the pipe 40 coming from the transfer switch with the hole 150, and so with the interior of the bellows 42.

Referring to Figures 1, 3, 5 and 7, hole 152 connecting with the interior of the bellows is connected by a passage 153 in casting 76 with the pipe 49 going to the reset restriction 50.

Reset bellows 45 (referring to Figure 7), is closed at its fixed end by a plate 154 to which is secured a rod 155, which performs several functions. It extends into the bellows, and provides a limit stop. It is bored at 156 to provide a passage into the bellows. It is threaded at 157 to receive a nut 159, which clamps the bellows to the casting 76. The casting is slotted at 158 (Figure 4) to receive the extension of the rod 155. To assemble the reset bellows in position, it is

necessary only to slide the rod extension 155 through the slot 158, locate the aligning stud 97 in position, and tighten the nut 159.

Extending from the passage 156 is a flexible metal tubing 51, which carries a conventional fluid-tight connection 162 (Figure 1) which is detachably secured to the end of the resistance 50 opposite that to which the tubing 49 is secured.

Relay valve

Referring to Figures 3 and 16, the relay valve is a complete unit removable from the casting 76 by taking out screws 105. The relay valve body is made up of an outer cover plate 100, a body 101, and an inner cover plate 102. A gasket 103 is provided between the cover plate 100 and the body 101, and a gasket 104 is provided between the body 101 and the inner cover plate 102. The three screws 105 pass through the relay valve and thread into the frame casting 76, and hold the relay valve tight against the frame casting. A gasket 106 is provided between the inner cover plate 102 and the frame casting 76, and serves as a seal to prevent escape of air from the air passages that will be described going from the frame casting to the relay valve. The outer cover plate 100 is secured to the body 101 by three screws 107. Referring to Figure 16, three screws 108 hold the inner cover plate 102 to the body 101.

The restricted flow of air to the nozzle 27 (Fig. 2) is supplied by the restrictor 29 mounted in the relay valve 31. To this end, referring to Figures 2, 3, and 16, the pipe 32 supplying air to the relay valve is connected by conventional means to a port and passage 109 in the frame casting 76. The port and passage 109 enters the frame casting parallel to the front of the instrument and runs into a passage 110, extending forwardly from the passage 109. As shown in Figures 14 and 15, the inner cover plate 102, the body 101, and the gaskets are provided with aligning passages 110a which align with the passage 110, which passage carries the air supply to a supply chamber 111 formed by a cutout portion in the body 101 and by the gasket and outer cover plate 103 and 100.

Referring to Figures 2 and 15, the restriction 29 which provides a restricted flow of air to the nozzle is embodied in the frame work of the relay valve 31. The air is supplied to the restriction directly from the supply chamber 111. Referring to Figure 15, threaded into a passage 112 in the body 101 is a bushing 113 which carries a glass bead 114, provided with a small passage 115, which passage 115 forms the restriction that permits a restricted flow of air to flow to the nozzle. The passage 115 communicates with the passage 112 and with a passage 28b provided in the body 101, the gasket 104, the inner cover plate 102, gasket 105 and enters a "nozzle capacity chamber" 28a formed by a depression in the frame casting 76, and by the gasket 106 and the inner cover plate 102.

As shown in Figures 16 and 4, a passage 28 extends upwardly from the nozzle capacity through the frame casting 76, then forwardly and then to the left through the casting 76 to the opening 11. The hollow stud 74 (Figure 17) conducts the air flow to the nozzle 27.

Returning to Figure 15, to clear the restriction 115 in the glass bead 114 from dirt or other foreign matter in the event that such becomes lodged in the restriction, a fine wire 116 is mounted on a plunger 117, carried in a threaded sleeve 118, threaded into the body 101 as shown. A head 119 is provided on the plunger 117 for

depressing the plunger against the action of a compression spring 129. When the plunger 113 is depressed, the wire 116 is caused to pass through the restriction 115. To assure the wire 116 entering the restriction 115, the surfaces 121 of the bead 114 and the bushing 113 are shaped to a generally concave contour. To prevent escape of air to the atmosphere past the plunger 117 when it is in its normal position with the wire 116 withdrawn from the restriction 115, a 10 valve body 122 is mounted on the plunger 117 and seats against the sleeve 118.

Referring to Figures 2 and 14, the flow of air from the supply chamber 111 to the proportioning bellows 42 is controlled by an inlet valve body 123, which is a hardened steel ball. The exhaust to atmosphere is regulated by an exhaust valve body generally indicated at 124 and having a conically-shaped head 125 and an operating stem 126. The ball 123 controls the flow of air into a chamber 127 formed by a hardened steel sleeve 128 mounted in the body 101. The flow of air out of the chamber 127 is controlled by the valve head 125, and after passing the valve head, flows through a chamber 129 and through flues 44 (Figure 14) to the atmosphere. The air pressure in the chamber 127 is the output pressure of the controller.

Referring to Figure 13, this output pressure is conducted from the chamber 127 by a passage 38 which extends upwardly through the body 101 to a horizontal passage 38a provided in the body 101 (Figure 16), the gasket 104, the cover plate 102, and the gasket 106, and communicates with a corresponding passage 38b in the casting 76. The pipe 39 leading to the transfer switch 33 connects with the passage 38b.

Turning again to Figure 14, the valve body 124 is mounted on a plate 138, suitably secured and centered with respect to the diaphragm 37. The diaphragm 37 in turn is clamped between the gasket 104 and the body 101 by the inner cover plate 102. The diaphragm extends rearwardly into an indentation 131 provided in the inner cover plate 102.

The pressure back of the nozzle 27 communicates with the side of the diaphragm 37 facing the nozzle capacity 28a, through a small hole 132 provided in the cover plate 102. Pressure on the diaphragm 37 moves it forwardly against the action of its spring characteristic. As the forward motion continues the stem 126 contacts the ball 123, uncovering the inlet port of the sleeve 128. If the motion continues, the valve head 125 seats on the sleeve 128, closing off the chamber 127 from atmosphere. The initial tension on the diaphragm 37 is preferably such that when a pressure of approximately $\frac{1}{4}$ lb./sq. in. exists on the diaphragm 37, the stem 126 is moved forwardly to contact the ball 123, but this leaves the exhaust port wide open to atmosphere. As the valve stem 126 moves the ball 123 from its seat, the valve body 125 starts closing off the exhaust to atmosphere and the air pressure in the chamber 127 and in the proportioning bellows increases. The maximum pressure in the chamber 127 exists when the valve body 124 seats against the sleeve 128. The minimum pressure in the chamber 127 exists when the valve stem 126 allows ball 123 to seat against the sleeve 128. For intermediate positions of the stem 126, intermediate pressures between the maximum and minimum pressures are caused to exist in the chamber 127.

The construction of these parts making up the relay valve are such that a travel of the dia-

phragm of only approximately .01 of an inch is required to produce a maximum change in the output pressure.

An advantage of the present construction is that a simple aligning procedure minimizes possibility of misalignment of the valve bodies 123 and 124. Misalignment of the body 124 is eliminated by the manner in which the diaphragm 37 is constructed and mounted. In assembling the diaphragm 37 properly to align it, the cover plate 102 is placed over the diaphragm, but loosely held. A pin or other suitable point is pressed through the opening 132 to force the valve head 125 against the seat 128. This serves accurately to align the diaphragm 37 so that as the pressure on it increases, the valve head 125 aligns correctly with the valve seat provided by the sleeve 128. After the diaphragm 37 is thus depressed, the screws 103 are tightened to clamp the diaphragm 37 tightly between the plate 102 and the body 101.

Another advantage of the construction is that the valve head 125 may be mounted close to the diaphragm so that any distortion of the diaphragm from its vertical plane has only a minimum effect on the alignment of the valve head 125 and its valve seat. This construction is facilitated by dishing the diaphragm 37 as shown in Figure 14 to permit the exhaust air to flow past the diaphragm through the flues 44, and by bringing the gasket 103 over the rim of the diaphragm to seal the space 131 surrounding the side of the diaphragm exposed to the nozzle back pressure.

Referring to Figure 14, the valve 123 is held in alignment by a hole 133 provided in a spring 134, supported on two posts 135 by screws 136 threaded into the body 101. At the time the ball and spring are assembled, to secure accurate alignment, the spring 134 is pressed downwardly against the ball while the screws 136 are loose. The screws are then tightened. Thus, the spring 134 guides the ball 123 accurately with respect to its seat as the ball is pushed away from its valve seat, and insures the ball coming back to the left.

The spring 134 not only serves to guide the valve body 123, but also provides an adjustable spring characteristic against which the diaphragm 37 operates. The spring characteristic is made adjustable by providing a second flexure spring 137 secured by the screws 136 and overlying the spring 134. The flexure spring 137 is stiffer than the flexure spring 134, and carries an adjusting screw 138. As the screw is turned in through the flexure spring 137, the spring tension on the ball 123 is increased, and as the screw is threaded out through the spring 137, the tension is decreased. A lock nut 139 secures the adjustment of the screw 138.

The correct adjustment of the initial spring tension on the ball 123 can be made after the relay valve is finally assembled, through an opening 140 provided in the outer cover plate 100 and aligned with the screw 138. A threaded cap 141 normally closes the opening 140.

The spring tension on the ball 123 is preferably adjusted so that the ball does not start to lift from its seat until a pressure of approximately 2 lb./sq. in. exists on the diaphragm 37. The overall spring characteristic is so related to the spring characteristic of the diaphragm 37 and to the area of the diaphragm 37 that a change of pressure on the diaphragm 37 of approximately $\frac{1}{2}$ lb./sq. in. is required to produce maximum

change of the output pressure in the chamber 127 and in the proportioning bellows 42.

Referring to Figures 14 and 19, a preferred construction of the diaphragm 37 is shown. The diaphragm which is made of a suitable material such as .004 beryllium copper is cupped and is provided with radially extending depressions. Using this type of diaphragm, as the pressure on the diaphragm increases, the amount of diaphragm movement or travel decreases for a given pressure change on the diaphragm. Also with the construction disclosed, the diaphragm has a relatively large motion for a relatively small pressure change back of the nozzle.

The nozzle capacity 28a previously described, together with the restriction provided by the small hole 132, serves to damp out pneumatic oscillations which might otherwise occur under some circumstances due to the interactions of the nozzle-flapper, relay valve, and proportioning bellows.

Transfer switch

Returning now to Figure 2, the air piping system is shown with couplings 163 in the lines 32, 39 and 40, which couplings may be broken so that (as shown in Figure 1) the backing plate and control mechanism mounted on it may be removed from the casing.

As shown in Figures 2 and 18, the transfer switch 33 has four positions. The automatic position is shown in Figure 2, in which the controller is connected to operate as has been described. To this end, a switch valve such as shown and described in the Mason Patent No. 2,476,104, is utilized. Such a switch valve contains a base portion 164 which has six ports arranged as shown and connected with the piping as shown. Over the ports is a cover 165 provided with three internal grooves facing the base 164. These grooves are numbered respectively 166, 167, and 168.

In the automatic position groove 167 connects the ports connecting pipes 32 and 34, so that the air supply is delivered to the relay valve. Groove 166 connects the pipe 39 with the pipe 40 going to the proportioning bellows. It also connects a pipe 48 with the pipe 39 coming from the relay valve, which pipe 48 goes to a diaphragm motor or other device.

When the cover 165 is turned to the manual position, as shown in Figure 18, the output pressure from the relay valve instead of being connected to the valve motor and to the proportioning bellows is dead ended. So although groove 167 still connects the supply pipe 34 to the supply pipe 32 going to the relay valve, the output pressure of the relay valve performs no control function. In this position, however, the groove 166 now connects the proportioning bellows 42 and the diaphragm motor with the pipe 170 connected with the output side of a conventional pressure regulator 171. The pressure regulator 171 is supplied with the regular air supply of 17 lbs./sq. in. through the pipe 35a, and is manually operated by means of knob 172 to supply to the pipe 170 any pressure desired below the supply pressure. A gauge 173 is connected to the line 170 to indicate the pressure from the line.

Thus, by turning the knob 172, any desired pressure may be supplied to the diaphragm motor. In practice, in starting up a process and getting it ready for automatic control, the transfer switch 33 would be thrown to its manual position, and the pressure on the diaphragm valve would be manually controlled through the regu-

lator 171 until the process had been brought to a condition suitable to turn it over to automatic control. But because in the manual control position the transfer switch also supplies the air pressure to the proportioning bellows, the proportioning and reset bellows are exposed to the same pressure being supplied to the diaphragm motor, just as when on automatic control.

When it is desired to throw the switch from manual control to automatic control after the process has manually been brought close to the set point, the control point setting mechanism is moved until the output of the relay valve 31, as indicated by the gauge 93, is brought within the range of, for example, 5 to 10 lbs.

Because in this setting of the transfer switch, the control mechanism operates essentially as an on-off controller, an output pressure between 5 and 10 lbs. indicates an almost exact alignment of the control point setting mechanism with the measuring element; i. e., the lever 14 as held by bellows 42 is moved by link 13 to bring the nozzle and flapper into tangency. Then when the transfer switch is later thrown to automatic position, the transfer is conveniently made without producing any material upset or change of pressure in the instrument, or on the diaphragm motor because the nozzle and flapper are properly aligned in their operating position as they would have been held by the proportioning bellows 42 had the instrument been on automatic control. After the instrument is turned on to automatic control, the final adjustment of the control point setting is made to bring the control point to the exact value desired.

When the transfer switch is moved to test position as shown in Figure 18, the diaphragm motor is connected by the groove 166 with the output of the manual regulator so that the process being controlled is actually under manual control. The groove 167 still connects the supply pipe 34 with the supply pipe 32 going to the relay valve. The output of the relay valve is now fed back by the connection of groove 166 to the proportioning bellows, but is not connected to the diaphragm motor pipe 48. This condition is useful when it is desired to test the instrument for various purposes while its measuring element is responsive to the process, but while its output pressure is not controlling the process.

When the transfer switch is moved to service position as shown in Figure 18, the supply pipe 32 going to the relay valve is shut off so that no pressure at all is delivered to the control instrument. The groove 174 connects the output of the manual regulator to the diaphragm motor so that the process may be manually controlled. But because no air is supplied to the control instrument, the entire control mechanism may be removed for repair or exchange leaving the process on manual control with the gauge 173 indicating the pressure being supplied to the diaphragm motor.

As many embodiments may be made in the above invention and as many changes may be made in the embodiment above described, it is to be understood that all matter hereinbefore set forth or shown in the accompanying drawings is to be interpreted as illustrative only and not in a limiting sense.

I claim:

1. In control apparatus including movable condition-responsive means, control means having a member having a neutral position and operated by said condition-responsive means, in combination, a crank pivoted about a fixed axis and

having a driving and a driven arm, and a bell-crank pivoted about a movable axis revolvable about said fixed axis and having a driving and a driven arm, connecting means connecting said condition-responsive means and the driving arm of said crank, connecting means connecting the driven arm of said crank and the driving arm of said bell-crank, and connecting means connecting the driven arm of said bell-crank and said member, the locus of the point of connection between said latter driven arm and its associated connecting means passing through said fixed axis, means for adjusting the angular relationship of said driving and driven arms of said crank to adjust said driven arm with respect to said condition-responsive means, and means for locking said bell-crank with respect to said fixed axis to hold said point of connection in a neutral position, whereby to hold said member in its said neutral position.

2. In control apparatus including movable condition-responsive means, control means having a member having a neutral position, and operated by said condition-responsive means, and a case for housing said control apparatus, in combination, a crank pivoted about a fixed axis and having a driving and a driven arm, a supporting arm pivoted about said fixed axis, a differential lever pivotally mounted on said supporting arm about an axis spaced from said fixed axis and having a driving and a driven arm, connecting means connecting said condition-responsive means and the driving arm of said crank, connecting means connecting the driven arm of said crank and the driving arm of said differential lever, and connecting means connecting the driven arm of said differential lever and said member the locus of the point of connection between said latter driven arm and its associated connecting means passing through said fixed axis, indicating means supported from the driving arm of said crank, means extending to the front of said case for adjusting the angular relationship of the driving and driven arms of said crank to adjust the relationship between the condition-responsive means and said indicating means without disturbing the relationship between said differential lever and said crank, and means for angularly adjusting said supporting arm about its axis to adjust the relationship between said neutral position and said condition-responsive means to change the control point of said control apparatus.

3. In control apparatus for establishing an output pressure variable in response to a condition being measured and including condition-responsive means, valve means for regulating a supply of energy to establish said pressure and follow-up motor means movable in correspondence with variation of said pressure, in combination, a mechanical system for mechanically interconnecting said condition-responsive means, said valve means and said follow-up motor means, including a floating lever connected at one end to said condition-responsive means and at its other end to said follow-up motor means, the directions of motions imparted to the respective ends of said floating lever respectively by said condition-responsive means and said follow-up motor means being at substantially right angles, and a cam having a cam surface and a cooperating cam-surface-engaging member mechanically connecting said floating lever and valve means to provide for operation of said valve means by said floating lever and to provide for free relative

motion therebetween, said follow-up motor means in response to the output of said valve means serving to move its end of said floating lever in accordance with the extent of movement of the other end by said condition-responsive means as modified by the slope of said cam surface with respect to the said directions of motion whereby the output pressure varies in accordance with the movement of said condition-responsive means.

10 4. In control apparatus for establishing an output pressure variable in response to a condition being measured and including condition-responsive means, valve means for regulating a supply of energy to establish said pressure and follow-up motor means movable in correspondence with variation of said pressure, in combination, a mechanical system for mechanically interconnecting said condition-responsive means, said valve means and said follow-up motor means, including a floating lever connected at one end to said condition-responsive means and at its other end to said follow-up motor means, the directions of motions imparted to the respective ends of said floating lever respectively by said condition-responsive means and said follow-up motor means being at substantially right angles, and a cam having a cam surface and a cooperating cam-surface-engaging member mechanically connecting said floating lever and valve means to provide for operation of said valve means by said floating lever and to provide for free relative motion therebetween, said follow-up motor means in response to the output of said valve means serving to move its end of said floating lever in accordance with the extent of movement of the other end by said condition-responsive means as modified by the slope of said cam surface with respect to the said directions of motion whereby the output pressure varies in accordance with the movement of said condition-responsive means, and means for changing the slope of said cam surface to vary the amount of change of said output pressure caused by a given movement of said condition-responsive means.

45 5. In control apparatus for establishing an output pressure variable in response to a condition being measured and including condition-responsive means, valve means for regulating a supply of energy to establish said pressure and follow-up motor means movable in correspondence with variation of said pressure, in combination, a mechanical system for mechanically interconnecting said condition-responsive means, said valve means and said follow-up motor means, including a floating lever connected at one end to said condition-responsive means and at its other end to said follow-up motor means, the directions of motions imparted to the respective ends of said floating lever respectively by said condition-responsive means and said follow-up motor means being at substantially right angles, and a cam having a cam surface and a cooperating cam-surface-engaging member mechanically connecting said floating lever and valve means to provide for operation of said valve means by said floating lever and to provide for free relative motion therebetween, said follow-up motor means in response to the output of said valve means serving to move its end of said floating lever in accordance with the extent of movement of the other end by said condition-responsive means as modified by the slope of said cam surface with respect to the said directions of motion whereby the output pressure varies in accordance with the movement of said condition-responsive means.

means, and means for changing the slope of said cam surface to vary the amount of change of said output pressure caused by a given movement of said condition-responsive means, said cam surface slope being adjustable about an axis determined by a neutral position of said cam surface-engaging member, in which position adjustment of said cam surface causes no change of output pressure.

6. In control apparatus, in combination, control mechanism regulating the value of an output pressure, a floating lever, a cam having a cam surface and a cooperating cam-surface-engaging member mechanically connecting said floating lever and control mechanism to provide for operation of the latter by movement of the former, responsive means responsive to deviation of a measured condition from a neutral value, for positioning one end of said floating lever with respect to a neutral position in accordance with the magnitude and direction of the deviation of said responsive means from its neutral value, follow-up motor means movable against a spring characteristic with respect to a neutral position in response to changes of said pressure for moving the other end of said floating lever with respect to its neutral position, whereby said follow-up motor means in response to change of said responsive means moves its end of said floating lever amounts related to the movement of said responsive means, as modified by the slope of said cam surface, and means for adjusting the relative position of said cam surface and cam surface-engaging member to bring them into a neutral relationship when the ends of said floating lever are in their respective neutral positions.

7. In control apparatus, in combination, control mechanism regulating the value of an output pressure and having a cam surface, a floating lever having a cam surface-engaging member contacting said cam surface to provide for operation of said control mechanism by movement of said floating lever, condition-responsive means for moving one end of said floating lever in either of two opposing directions, follow-up motor means responsive to variation of said pressure for moving the other end of said lever in either of two opposing directions generally at right angles to the first two opposing directions, said follow-up motor operating to move its end in a direction and magnitude related to the direction and magnitude of movement of the other end by said condition-responsive means as modified by the slope of said cam surface, said control mechanism and cam surface being revolvable about an axis to change the slope of said cam surface to change the magnitude of movement of said follow-up motor means in response to a given movement of said condition-responsive means.

8. In control apparatus, in combination, valve means including a pivoted lever for regulating pressure in a pneumatic system, a floating lever including a member for engaging said pivoted lever to operate said valve means, a pair of opposing bellows for supporting and moving one end of said floating lever, condition-responsive means responsive to deviation of a measured condition from a neutral value for moving the other end of said floating lever with respect to said neutral position in accordance with the magnitude and direction of deviation of said responsive means from its neutral value, spring means for holding the end of said floating lever supported by said bellows in a neutral position when the pressures in said bellows are equal, one of said

bellows being connected with the output of said valve means to move said floating lever amounts related to movement of said floating lever by said condition-responsive means, means for rotating said valve means about an axis substantially aligned with the point of engagement of said pivoted lever and said member when said floating lever is at said neutral position for changing the amount of movement produced by the said bellows for a given movement of said floating lever by said condition-responsive means, and means providing a restricted passage between the said bellows and the other of said bellows.

9. In control apparatus of the class described, in combination, valve means, an operating lever for operating said valve means and having a cam surface, a floating lever, an operating member carried by said floating lever for actuating said operating lever by contact along said cam surface, condition-responsive means for freely moving one end of said floating lever in one of two opposing directions in response to changes of said condition-responsive means, spring opposed follow-up motor means responsive to changes of output of said valve means for freely moving the other end of said floating lever in one of two opposing directions generally at right angles to said first two opposing directions, and acting to move its end of said floating lever amounts related to the extent of movement of the other end by said condition-responsive means and to the slope of said cam surface, said operating lever being pivoted about an axis revolvable about said operating member when at a neutral position whereby the angular relationship between the cam surface of said operating lever and said direction of movement may be adjusted to change the magnitude of motion imparted to said floating lever by said follow-up motor means in response to a given movement of said condition-responsive means.

10. In control apparatus of the class described, in combination, a nozzle-flapper pilot valve revolvable as a unit about an axis, a flapper-operating lever pivoted about an axis revolvable with the nozzle-flapper valve and having a cam surface, a floating lever, an operating member carried by said floating lever for operating said flapper-operating lever by contact along said cam surface, condition-responsive means for freely moving one end of said floating lever in either of two opposing directions in response to changes of said condition-responsive means, a spring opposed bellows motor for freely moving the other end of said floating lever in either of two opposing directions generally at right angles to said first opposing directions, and in amounts related to the magnitude of movement by said condition-responsive means and to the slope of said cam surface, and means for revolving said nozzle-flapper and flapper-operating lever about the first of said axes to adjust the magnitude and direction of motion imparted to said floating lever by said bellows motor in response to a given movement of said condition-responsive means.

11. In control apparatus of the class described, in combination, a nozzle-flapper pilot valve revolvable as a unit about an axis, a flapper-operating lever pivoted about an axis revolvable with the nozzle flapper valve and having a cam surface, a floating lever, an operating member carried by said floating lever for operating said flapper-operating lever by contact with said cam surface, condition-responsive means for freely moving with respect to a neutral position one end

of said floating lever along a path in either of two opposing directions in response to changes of said condition-responsive means, follow-up motor means for freely moving with respect to a neutral position the other end of said floating lever in either of two opposing directions along a path generally at right angles to said first path, and in amounts related to the magnitude of movement by said condition-responsive means and to the slope of said cam surface, means for revolving said nozzle-flapper and flapper-operating lever about said axis to change the magnitude and direction of motion imparted to said floating lever by said bellows motor in response to a given movement of said condition-responsive means, and adjusting means contained by said floating lever for adjusting said operating member with respect to said floating lever when its ends are in their respective neutral positions in directions parallel to both of said paths to align said operating member with respect to the axis about which the nozzle-flapper pilot valve is revolvable.

12. In control apparatus of the class described, in combination, a follow-up bellows secured at one end, a flexure spring member opposing motion of the other end of said bellows, a floating lever supported at one end from said spring member, and at its other end by a measuring element, and a nozzle-flapper pilot valve operated by said floating lever, the output of which pilot valve controls pressure supply to said follow-up bellows.

13. In a controller of the class described, a freely movable measuring element, a nozzle-flapper pilot valve, a bellows motor rigidly supported at one end and having its free end opposed by a flexure spring member having one end secured and having a free end, the free end of said spring and said measuring element being effectively connected to said pilot valve to conjointly operate said pilot valve, and means responsive to the output of said pilot valve for supplying pressure to said bellows motor whereby movement of said measuring element acting on said pilot valve produces a corresponding movement of said bellows motor and a corresponding change of pressure therein.

14. In control apparatus of the class described, in combination, valve-operating means having in the same plane two components of motion with respect to a neutral axis perpendicular to said plane, valve means movable by said valve-operating means about an axis perpendicular to said plane and spaced from said neutral axis, and adjusting means for revolving said valve means and its axis about said neutral axis to adjust the magnitude and direction of motion imparted to said valve means by one of said components of motion, and to adjust the magnitude of the motion by the other in reverse ratio.

15. For use in pneumatically operated mechanism, in combination, a relay valve including a housing having a pressure supply chamber, a passage connecting said supply chamber with the atmosphere and an output pressure port communicating with said passage, a ball valve for controlling the opening at one end of said passage, a cantilever spring member extending across said opening and at right angles to the passage and having means aligned with said opening for receiving said ball, said spring being adapted to urge said ball against said opening and to guide said ball as it is moved away from said opening, means for moving said ball against the action of said spring member including a diaphragm, a stem extending from said diaphragm through

said passage and contacting said ball whereby pressure variation on said diaphragm moves said ball with respect to said opening, and a valve body associated with said stem for controlling the opening at the other end of said passage whereby, as said diaphragm moves said ball from the opening associated therewith, the valve body moves to close the opening associated with it, and regulates the pressure in the output port.

16. For use in pneumatically operated mechanism, in combination, a relay valve including a housing having a pressure supply chamber, a passage connecting said supply chamber with the atmosphere and an output pressure port communicating with said passage, a ball valve for controlling the opening at one end of said passage, a cantilever spring member extending across said opening and at right angles to the passage and having means aligned with said opening for receiving said ball, said spring member being adapted to urge said ball against said opening and to guide said ball as it is moved away from said opening, means for moving said ball against the action of said spring member including a diaphragm, a stem extending from said diaphragm through said passage and contacting said ball whereby pressure variation on said diaphragm moves said ball with respect to said opening, a valve body associated with said stem for controlling the opening at the other end of said passage whereby, as said diaphragm moves said ball from the opening associated with the ball, the valve body carried by said stem moves to close the opening associated with said valve body and regulates the pressure in the output port, and means for supplying a variable pressure to one side of said diaphragm.

17. For use in pneumatically operated mechanism, in combination, a relay valve including a housing having a pressure supply chamber, a passage connecting said supply chamber with the atmosphere, a ball valve for controlling the opening at one end of said passage, a cantilever spring member extending across said opening and at right angles to the passage and having means aligned with said opening for receiving said ball, said spring being adapted to urge said ball against said opening to guide said ball as it is moved away from said opening, means for moving said ball against the action of said spring member including a diaphragm, and a stem extending from said diaphragm through said passage and contacting said ball whereby pressure variation on said diaphragm moves said ball with respect to said opening, and a second spring member overlying said cantilever spring member adapted to provide an adjustable initial spring tension holding said ball against said opening.

18. For use in pneumatically operated mechanism, in combination, a relay valve including a housing having a pressure supply chamber, a passage connecting said supply chamber with the atmosphere, a ball valve for controlling the opening at one end of said passage, a cantilever spring member extending across said end and at right angles to the passage and having means aligned with said opening for receiving said ball, said spring member being adapted to urge said ball against said opening and to guide said ball as it is moved away from said opening, and means for moving said ball against the action of said spring member including a diaphragm, a stem extending from said diaphragm through said passage and contacting said ball whereby

pressure variation on said diaphragm moves said ball with respect to said opening, said diaphragm being formed of beryllium copper and provided with radially extending indentations.

19. For use in pneumatically operated mechanism, in combination, a relay valve including a body member, a pressure supply chamber on one side of said body, a passage through said body member connecting said chamber with the atmosphere, a first valve body controlling flow of air from said supply chamber to said passage, a second valve body controlling the flow of air from said passage to the atmosphere, a cupped metal diaphragm concentric with and overlying closely the exhaust side of said passage and supporting said second valve head, a passage through said body member connecting the inside of said diaphragm with the atmosphere, a cover member overlying said diaphragm, and providing an air chamber outside said diaphragm, said cover member sealing the edges of said diaphragm against air passage, and an entrance to said latter chamber to permit air pressure variation therein to operate said diaphragm and said second valve body.

20. In pneumatically operated control apparatus including a nozzle-baffle pilot valve in which the nozzle is supplied with a restricted flow of air and variation of flapper position with respect to the nozzle varies the nozzle back-pressure in accordance with a non-uniform characteristic relationship, in combination, a relay valve responsive to the nozzle back-pressure and including a housing having a pressure supply chamber, a passage connecting said supply chamber with the atmosphere, double acting valve means for simultaneously controlling the supply of air to and the exhaust of air from said passage, spring means urging said valve means in one direction, a metal diaphragm for moving said valve means against the action of said spring means, said diaphragm being dish-shaped whereby by selection of said diaphragm thickness and of the spring characteristic of said spring means, said diaphragm and spring means may be adjusted to give said relay valve a non-uniform characteristic such as to counteract the non-uniform characteristic of said nozzle-flapper pilot valve.

21. In control apparatus of the class described including a measuring element, a nozzle-flapper pilot valve, a relay valve pneumatically connected to the pilot valve back-pressure and having a movable part operated by the pilot valve back-pressure, and follow-up bellows operated by the relay valve output pressure, a lever having appreciable inertia and operated conjointly by said measuring element and said follow-up bellows for operating said pilot valve, a pneumatic capacity in the connection between said pilot valve and said relay valve located close to the said operating part of said relay valve, and a pneumatic restriction between said capacity and said movable part whereby high frequency oscillation of said pilot valve, relay valve and follow-up bellows are eliminated.

22. In a pneumatically operated controller of the class described, including a measuring element, a pilot valve having a variable back-pressure, a relay valve having a variable output pressure responsive to the pilot valve back-pressure, a follow-up motor responsive to the relay valve output pressure and operating the pilot valve in conjunction with the measuring element, and a valve motor operated by the

relay valve output pressure, in combination, a pneumatic circuit including a regulated source of supply pressure, switching means movable to any one of four positions respectively designated as automatic, manual, test and service, first piping connecting said switching means with the supply side of said relay valve, second piping connecting the output of said relay valve with said switching means, third piping connecting said switching means, follow-up motor with said switching means, fourth piping connecting said supply pressure with said switching means, fifth piping connecting said switching means with said valve motor, a manually operable reducing valve connected with said regulated supply pressure, and sixth piping connecting the reducing valve output with said switching means, said switching means being so constructed and arranged that when in automatic position it acts to connect said first and fourth piping to supply pressure to the nozzle-baffle pilot valve and relay valve and to connect said second and third piping to supply said relay valve output to said follow-up motor, and to connect said second and fifth piping to supply said relay valve output to said valve motor, and to shut off said sixth piping; and when in manual position to connect said first and fourth piping to supply pressure to said nozzle-baffle pilot valve and relay valve, and to connect said third, fifth and sixth piping to supply the reducing valve output to said valve motor and said follow-up motor, and to shut off the second piping to close up the relay valve output; and in test position to connect said first and fourth piping to supply air to said nozzle-baffle pilot valve and relay valve, and to connect said second and third piping to supply the relay valve output to said follow-up motor, and to connect said fifth and sixth piping to supply the reducing valve output to said valve motor; and in service position to shut off said first and fourth piping and to connect said fifth and sixth piping to supply the reducing valve output to said valve motor whereby said first, second and third piping may be disconnected from said switching means; a first pressure gauge continuously connected to said second piping, and a second pressure gauge continuously connected to said sixth piping, said gauges being visible at the same time whereby when in manual position the nozzle and flapper may be brought into tangency, so that when the switching means is moved to automatic position, there is no change of pressure in the controller and no change of pressure being supplied to the valve motor.

23. In control apparatus for moving a part in correspondence with variations of a measured condition, in combination, condition-responsive means, valve means for regulating supply of air pressure, and follow-up motor means movable in response to said air pressure and connected to move said part, mechanism including a Watts straight-line mechanism for interconnecting said condition-responsive means, said valve means and said part, said Watts straight-line mechanism having a floating lever connected to two connecting links one pivoted about a fixed pivot and one pivoted about a movable pivot, means for moving said movable pivot in response to movements of said measuring element along a path substantially at right angles to the path of straight line motion of the floating lever, and means for pivoting the link pivoted about the fixed pivot in response to movements of said part by said follow-up motor means, a cam

having a cam surface and a cooperating cam-surface-engaging member mechanically connecting the point of straight line motion of the floating lever and said valve means to provide for operation of said valve means by said floating lever and to provide for free relative motion therebetween, said follow-up motor means in response to the regulated supply of air pressure by said valve means serving to move said part to pivot said link about said fixed center, and thereby move said part and said floating lever in accordance with the extent of movement of the movable pivot by said condition-responsive means as modified by the slope of said cam surface with respect to the path of straight line motion of the floating lever.

24. In control apparatus for moving a part in correspondence with variations of a measured condition, in combination, condition-responsive means, valve means for regulating supply of air pressure, and follow-up motor means movable in response to said air pressure and connected to move said part, mechanism including a Watts straight-line mechanism for interconnecting said condition-responsive means, said valve means and said part, said Watts straight-line mechanism having a floating lever connected to two connecting links one pivoted about a fixed pivot and one pivoted about a movable pivot, means for moving said movable pivot in response to movements of said measuring element along a path substantially at right angles to the path of straight line motion of the floating lever, and means for pivoting the link pivoted about the fixed pivot in response to movements of said part by said follow-up motor means, a cam having a cam surface and a cooperating cam-surface-engaging member mechanically connecting the point of straight line motion of the floating lever and said valve means to provide for operation of said valve means by said floating lever and to provide for free relative motion therebetween, said follow-up motor means in response to the regulated supply of air pressure by said valve means serving to move said part to pivot said link about said fixed center, and thereby move said part and said floating lever in accordance with the extent of movement of the movable pivot by said condition-responsive means as modified by the slope of said cam surface with respect to the path of straight line motion of the floating lever, and means for changing the slope of said cam surface to vary the amount of movement of said part produced by a given movement of said condition-responsive means, said cam surface slope being adjustable about the axis passing through the midpoint of the path of straight line motion of said floating lever.

25. In control apparatus for moving a part in correspondence with variations of a measured condition, in combination, condition-responsive means, valve means for regulating supply of air pressure, and follow-up motor means movable in response to said air pressure and connected to move said part, a mechanical system for mechanically interconnecting said condition-responsive means, said valve means and said follow-up motor means, including a floating lever connected at one end to said condition-responsive means and at its other end to said follow-up motor means, the directions of motions imparted to the respective ends of said floating lever respectively by said condition-responsive means and said follow-up motor means being

generally at right angles, a cam having a shaped cam surface and a cooperating cam-surface-engaging member mechanically connecting said floating lever and valve means to provide for operation of said valve means by said floating lever and to provide for free relative motion therebetween, said follow-up motor means in response to the output of said valve means serving to move said part and its respective end of said floating lever in accordance with the extent of movement of the other end of said floating lever by said condition-responsive means as modified by the shaped surface of said cam whereby said part is moved in correspondence with the movement of said condition-responsive means.

26. In control apparatus, in combination, valve means including a pivoted lever for regulating pressure in a pneumatic system, a floating lever including a member for engaging said pivoted lever to operate said valve means, a pair of opposing bellows for supporting and moving one end of said floating lever, condition-responsive means responsive to deviation of a measured condition from a neutral value for moving the other end of said floating lever with respect to said neutral position in accordance with the magnitude and direction of deviation of said responsive means from its neutral value, spring means for holding the end of said floating lever supported by said bellows in a neutral position when the pressures applied to said bellows are equal, one of said bellows being connected with the output of said valve means to move said floating lever amounts related to movement of said floating lever by said condition-responsive means, means for rotating said valve means about an axis substantially aligned with the point of engagement of said pivoted lever and said member when said floating lever is at said neutral position for changing the amount of movement produced by the said bellows for a given movement of said floating lever by said condition-responsive means, and means providing a restricted passage between the said bellows and the other of said bellows.

27. In control apparatus of the class described, in combination, a pilot valve comprising a nozzle and cooperating pivoted flapper, a flapper-operating lever mechanically connected to the flapper to move it with respect to said nozzle and having a cam surface, a floating lever, an operating member carried by said floating lever for operating said flapper-operating lever by contact along said cam surface, condition-responsive means for freely moving one end of said floating lever in either of two opposing directions in response to changes of said condition-responsive means, a spring opposed bellows motor for freely moving the other end of said floating lever in either of two opposing directions generally at right angles to said first opposing directions and in amounts related to the magnitude of movement of said condition responsive means and to the slope of said cam surface, and means for rotating said flapper and flapper-operating lever about the operating member of said floating lever to adjust the magnitude and direction of motion imparted to said floating lever by said bellows motor in response to a given movement of said condition responsive means.

28. In control apparatus of the class described, in combination, a pilot valve comprising a nozzle and cooperating pivoted flapper, a flapper-operating lever mechanically connected to said

flapper to move it with respect to said nozzle and having a cam surface, a floating lever, an operating member carried by said floating lever for operating said flapper-operating lever by contact with said cam surface condition-responsive means for freely moving with respect to a neutral position one end of said floating lever along a path in either of two opposing directions in response to changes of said condition-responsive means, follow-up motor means for freely moving with respect to a neutral position the other end of said floating lever in either of two opposing directions along a path generally at right angles to the first path and in amounts related to the magnitude of movement by said condition-responsive means and to the slope of said cam surface, means for rotating said flapper and flapper-operating lever about the operating member of said floating lever to change the magnitude and direction of motion imparted to said floating lever by said motor means in response to a given movement of said condition-responsive means, and adjusting means associated with said floating lever for adjusting said operating member with respect to said floating lever when its ends are in their respective neutral positions in directions parallel to either of said paths.

HOEL L. BOWDITCH.
